UNITED STATES PATENT OFFICE.

ARNOLD HENRY JESSEN, OF LOS ANGELES, CALIFORNIA, ASSIGNOR TO HYDRAULIC CLUTCH COMPANY, OF LOS ANGELES, CALIFORNIA, A CORPORATION.

VARIABLE-SPEED POWER-TRANSMITTING DEVICE.

1,336,749.

Specification of Letters Patent. Patented Apr. 13, 1920.

Application filed September 25, 1919. Serial No. 328,048.

To all whom it may concern:

Be it known that I, ARNOLD H. JESSEN, a citizen of the United States, residing at Los Angeles, county of Los Angeles, and 5 State of California, have invented a new and useful Variable-Speed Power-Transmitting Device, of which the following is a specification.

This invention relates to variable speed 10 power-transmitting devices and particularly to the type of devices shown and described in my former patent bearing Serial No. 1,105,792, and dated August 4, 1914, the present invention being an improvement 15 upon that type of mechanism.

It is an object of the present invention to provide a device of this kind with means for moving the pistons against the action of the liquids contained in the device, without a 20 tendency to cramp or exert lateral pressures upon the pistons, all pressure in moving the said pistons being substantially in a direction of straight thrusts longitudinally of the piston axes.

25 It is a further object of the invention to provide rocker arms for carrying the pistons of the device, whereby one end of each arm may be pivotally anchored, the free ends of the piston moving arms being thus given a 30 fixed range of movement.

It is also an object of the invention to interpose between the inner rotor of the device and the liquid moving pistons intermediate pivoted members connected with 35 the said pistons and adapted to bear against the cam of the device, whereby tangentially set pistons may be reciprocated without the tendency of lateral prying actions on the pistons and the consequent friction.

40 It is also a further object of the invention to provide a mechanism of the class referred to with a valve which is adapted to control the movement of the liquid which moves in and out of the cylinders of the rotor, mechanism being employed for controlling the 45 said valve, which is adapted to effect a metal to metal contact between the parts whereby the shell or casing of the apparatus will thus be not entirely dependent upon the 50 hydraulic agent used, in establishing the same speed in the driven member as that attained by the driving member.

With these and other objects in view the invention comprises certain novel constructions, combinations and arrangements of

parts as will be hereinafter more fully set forth and described.

In the accompanying drawing forming a part of this specification:

Figure 1 is a central longitudinal sectional view taken through a power-transmitting device forming the subject matter of the present invention.

Fig. 2 is an edge elevation of a portion of the rotor within the casing of the device 65 and showing one of the rocker members employed for moving the pistons in the rotor cylinders.

Fig. 3 is a detail transverse sectional view taken upon the line 3—3 of Fig. 1;

Fig. 4 is a sectional view taken upon the line 4—4 of Fig. 1.

Fig. 5 is a sectional view taken upon the line 5—5 of Fig. 1.

The improvement embodying the features 75 of the present invention is designed to obtain a better and more free action in the movement of the pistons employed in devices like that disclosed in my former patent above referred to. The details and features 80

of the mechanism will now be more specifically described, reference being had to said drawings in which 6 indicates an outer shell or casing, the said casing being pro-

vided with a larger portion adapted to re-

ceive the inner rotor 7, while a reduced portion of said casing, projecting from one

side thereof is adapted to receive the trains

of gearing employed in transmitting move-

ment from one portion of the mechanism 90

to the other. A plate or circular cover 8 is

removably secured to one side of the said

casing for permitting access to the interior

thereof and facilitating the assembling of

the mechanism within. The reduced portion 95

of the casing carries a bearing 9 preferably

of the ball type and carrying a shaft 10

which projects outside the casing and is pro-

vided with a flange 11 adapted to be bolted

or otherwise secured to the corresponding 100

flange 12 upon the shaft 13 of an engine or

other motor. A packing gland 14 surrounds

the said shaft 10 outside the ball bearing 9.

The inner end of the shaft 10 is reduced

and fits into an inner bearing 15 also of the

ball type, the said bearing being mounted

in a recess formed in the adjacent face of

the inner rotor or cylinder carrying member

7. The said rotor and shaft are thus mov-

ably held with respect to each other. Sur-

rounding the bearing 9 and rigidly secured to the wall of the shell or casing 6, is a gear 16, the teeth of which mesh with similar gears 17. The said gears 17 are carried by shafts 18, the inner ends of which are fastened to and carried by the rotor 7. The said gears 17 are preferably mounted upon ball bearings 19 carried by the said shafts 18 and secured upon the reduced end portions of said shafts. Upon a larger portion of said shafts 18 are ball bearings 20 upon which are mounted gears 21 of a larger diameter than the said gears 17. The preferable ratio in the size of said gears is two to one, the gears 21 being twice the diameter of the gears 17. There are preferably two trains of gears 17 and 21, the shafts of which are arranged diametrically opposite to each other upon the rotor 7, in order to properly balance the action of the mechanism. The gears 21 upon both sides of the device are in the same plane and their teeth mesh with an actuating pinion 22 rigidly secured upon the inner end portion of the shaft 10.

25 The arrangement of the parts is such that when the shaft 10 is rotated, it will turn the actuating pinion 22 and drive the gears 21. The said gears 21 are rigidly connected with gears 17, usually by keys or splines 23 so that the said gears turn together. The gears 17 will thus be given motion by the driving of the gears 21 and movement may thus be imparted from the gears 17 to the gears 16 upon the casing 6. 30 The said casing will thus be rotated about the shaft 10 and around the rotor 7.

The structure of the rotor is somewhat different from that shown in my former patent and is preferably provided with a 40 series of cylinders 24 set tangentially therein, instead of radially as in said former patent. There are preferably an even number of such cylinders, whereby one may be made to exactly balance another upon the 45 opposite side of the rotor axis. In the drawing four of such cylinders 24 have been shown. Moving in each cylinder is a piston 25 adapted to be connected by the usual pitman or connecting rod 26 with the free end 50 of a rocker arm or member 27, one such rocker member being provided for each cylinder. The end of the rocker arm opposite to the pitman 26 is in each case pivotally mounted between ears 28 which project from the sides of an adjacent cylinder. The pivoted end of the rocker arm is preferably provided with a single bearing portion 29 engaging a pin 30 carried by the 55 said ears 28. The intermediate portion of each rocker arm is usually bifurcated and spread centrally so as to receive a roller 31. The said roller 31 is journaled upon a pin or short shaft 32, the ends of which extend through bearings 33 formed centrally of the 60 rocker arm. The ends of the bifurcated

portions of each rocker arm are provided with bearings 34 which carry pivot pins 35 by which the rocker arm is connected with its pitman 26. The rollers 31 engage and run upon the inner face of a cam ring 36 secured within the larger portion of the casing 6. The rocker arms are then forced inwardly at intervals upon the cam ring for moving the pistons in the cylinders when the rotor is not moving at the same speed 70 as the shaft 10. In order to return the pistons to their outer positions the pivot pins 32 of the rocker arms, are extended upon one side of each arm so as to carry an anti-friction roller 37. The rollers 37 engage the outer edge or face of a cam ring 38, which is secured to the inner surface of the casing disk 8. The said pistons are thus positively moved in both directions by the engagement of the rollers 31 and 37 with their respective cams. The fluid employed and interposed between the driving and the driven parts of the mechanism, fills the casing 6 and the cylinders of the rotor 7 and usually passes into and out of the cylinders through ports 39 which extend to the central portion of the rotor where an annular chamber 40 is provided. Communication is had between said chamber and the space within the casing 6 through inclined ports 41 95 formed in the central portion of the rotor. When the said ports are open the fluid usually oil, may pass freely into the cylinders or from the same according to the movement of the pistons therein. The central portion of the rotor is provided with a hub portion 42 which fits upon the reduced end of a power-transmission shaft 43. The said shaft 43 fits within a sleeve 44, the inner end of which is enlarged to form an annular valve 45 having ports 46 therein which may be brought into coincidence with the ports 39 which lead into the ends of the cylinders. The said valve 45 finds a bearing in the material of the rotor, babbitt or other bearing material as at 64 being preferably arranged between the parts. The babbitt is also perforated opposite the ports 39 so as not to interfere with the passage of the fluid. The sleeve 44 is mounted in ball 115 bearings 47 at its inner end, the said ball bearings being carried by the plate 8. A packing gland at 48 is mounted within an annular recess formed in the inner end of said sleeve 44, whereby oil will be prevented 120 from escaping from the casing around the shaft 43. The helical spring 49 keeps the packing in proper condition, forcing a ring 50 against said packing at all times. The inner ends of each of the pistons 25 is provided with a valve 51, which fits in a valve seat formed in the said inner end of the piston. A spring 52 normally maintains the valve in seated position. When the pistons move inwardly the valve will be seated and 125 130

will force the fluid out through the port 39. When the piston moves outwardly again, the fluid will unseat the valve and press past it, ready to be propelled by the piston through 5 the said port 39.

The casing 6 is filled with fluid, which constitutes the hydraulic agent which is interposed between the cylinders and the valve whereby the cam is enabled by its engagement with the rocker arms to gradually bring the movement of the rotor to that of the casing 6, as the driven member or shaft of the device is brought up to the movement of the engine shaft. The said liquid therefore entirely fills the casing 6, and the cylinders, as well as the ports establishing communication between the cylinders and the said casing. When the ports 46 in the valve 45 are in coincidence with the openings into 15 the cylinders, the fluid can move freely in and out as the pistons reciprocate under the action of the turning cam. The liquid passing through the said ports will, however, be checked and prevented from moving by 20 the closing of said ports and the motion of the two members will be brought together. The valve 45 is operable by means of mechanism for turning the sleeve 44. The said sleeve 44 has one or more inclined slots 25 53, there being preferably two in number arranged one opposite to the other as shown in Figs. 1 and 3 of the drawings. The ends of said slots are preferably provided with short straight portions parallel with the 30 axis of the sleeve so that there may be a slight movement of the sleeve turning means at each end of the slot after the valve has been moved as far as required. In order to turn the said sleeve 44 an outer sleeve 35 54 is provided having inwardly projecting studs 55 carrying anti-friction rollers 56. The said rollers project into the slots 53, so that when the sleeve 54 is reciprocated, it will operate to turn the said sleeve 44 and 40 thereby the valve 45. In order to make the action of the sleeve 54 effective it must be prevented from turning with respect to the shaft 43 and the said shaft 43 is therefore many sided or provided with ribs as at 45 57 extending longitudinally thereof. The sleeve 54 is contracted at its outer end and made to fit upon the said ribs 57 so that the said sleeve may slip longitudinally upon the shaft 43 but must turn therewith. In order 50 to facilitate the shifting of the sleeve 54, a collar 58 is mounted upon suitable ball bearings upon the reduced end of the sleeve 54 and oppositely projecting pins 59 carried by said collar are engaged by a forked lever 55 60 whereby the collar may be moved longitudinally of the transmission shaft 43. The forked portions of the said lever are indicated at 60 in Fig. 1 of the drawing. The lever may be similar to any gear shifting 65 lever commonly employed on motor vehi-

cles, and may extend to any convenient point for operation by the chauffeur or other party in charge of the vehicle. When the sleeve 54 has been pushed inwardly to the inner limit of its movement, the movement of the transmission shaft with the inner rotor carried thereby, will have attained the same speed as that of the casing 6, and the inner end of the said sleeve 54 is therefore provided with a toothed ratchet portion 61 adapted to engage a similar toothed ratchet portion 62 which projects in the form of a hub like extension upon the central portion of the plate 8. The teeth of these ratchet portions will become interlocked when the sleeve 54 is pushed inwardly as far as possible, whereby the driving and driven parts of the mechanism will be connected by a positive metal to metal contact. 70

The mechanism is not only useful as a gear transmission device but is also capable of use as a brake and for this purpose any ordinary brake band 63 may be supported upon the outer peripheral surface of the 80 reduced portion of said casing 6 as clearly shown in Fig. 1 of the drawing. The brake band may be provided with the usual brake lining 65 for offering the necessary frictional engagement between the parts. 85

In the operation of the device, the shaft 10, after the motor vehicle has been started, will be rotated in unison with the engine shaft being positively connected therewith. The shaft will turn the gear 22 which in 100 turn will operate the intermeshing gears 21. These gears carrying the gears 17 will by reason of their engagement with the gear 16 tend to turn the casing 6. The casing will thus be carried about the shaft 10 and with 105 the valve 45 set so that the ports entering the cylinders are open, the cam 36 carried by the casing 6 will move the rollers 31 exactly according to the shape of the inner surface of the cam, while the cam 38 will 110 move them outwardly again by reason of its engagement with the rollers 37. The liquid within the casing and cylinders will merely move freely back and forth through the ports. As soon as it is desired to connect the casing 6 with the parts to be driven, the lever 60 is shifted so as to turn the valve 45 and gradually close the ports entering the cylinders. The hydraulic material moved by the pistons will thus be gradually 115 retarded and the friction of the cam 36 on the said rollers 31 will tend to cause the inner rotor 7 to turn with the casing 6. By the time the valve 45 has completely closed the cylinder ports, the hydraulic material 120 will have been halted in its movement and will become an abutment between the pistons and the said valve so that the rollers 31 and the rocker arms 27 carrying them can 125 no longer be pushed inwardly. In this con- 130

dition the inner rotor must turn positively with the outer casing 6 and motion will be transmitted from the said rotor to the power transmission shaft 43. The shape of the cam 36 is such that the movement of the fluid from one set of cylinders will be substantially allowed for by the inner movement of the pistons in other cylinders, when the valve 45 is open. In the present device 10 as illustrated four cylinders are employed and the low parts of the cam are opposite to each other while the high parts of the cam are also opposite. The rocker arms and the pistons thus directly oppose each 15 other, giving a very smooth operation in the running of the mechanism. The use of the rocker arms 27 is of importance and makes it possible to prevent any side twisting upon the pistons in the cylinders, the 20 pressure upon said pistons being always applied in substantially an endwise thrust extending longitudinally of the axis of the cylinders.

The substantial anchoring of one end of 25 each rocker arm to the pivotal point upon the inner rotor prevents the said rocker arms from moving except in the desired way. The use of the rocker arms thus facilitates the tangential arrangement of the pistons as illustrated in the drawing.

When the device is to have the brake applied, the valve 45 is open to permit a free movement of the liquids again and upon tightening the brake band the casing 6 will be brought to a standstill. The tendency to 35 rotate the train of gearing through the movement of the shaft 10, will begin to tend to drive the rotor in the opposite direction, thus at first retarding the movement of the 40 transmission shaft and if the brake is put on tight enough finally stopping it completely. If the casing 6 is held absolutely immovable, the engine would in that event drive the transmission shaft in a reverse 45 direction for backing the vehicle. The one simple mechanism heretofore described is thus capable of being used to drive the vehicle forwardly or rearwardly or to be employed more or less as a brake. It is evident 50 that the mechanical details of construction may be somewhat altered without departing from the spirit of the invention.

What I claim is:

1. In a transmission mechanism, in combination, a driven member, a driving member, tangentially positioned cylinders carried by said driven member, pistons in said cylinders, means for controlling the movement of the pistons, a cam ring carried by 55 said driving member, and a rocker arm for each piston having one end connected thereto, and the other end pivotally connected to said driven member, and cam ring engaging members carried by said rocker arms intermediate their ends.

2. In a transmission mechanism, a driving member and a driven member, tangentially arranged cylinders connected with the driven member, pistons therein, a hydraulic agent, valves controlling the movement thereof, rocker arms having fixed pivotal mountings with respect to the cylinders and movably connected with said pistons, a cam interposed between the driving member and the driven member, gearing actuated by the driving member and controlling said cam and means carried by the rocker arms for engaging said cam whereby the pistons will be actuated.

3. A mechanism of the class described comprising a driving member, a driven member carrying a series of cylinders, pistons mounted in said cylinders and adapted to act upon a hydraulic agent, a valve controlling the movement of said agent, a cam interposed between the driving member and the driven member, gearing actuated by the driving member for controlling the said cam, rocker arms pivoted at one of their ends to the cylinders and at their other ends connected with said pistons, a roller carried by each rocker arm and engaging the inner surface of the said cam, whereby the pistons will be driven inwardly upon portions of the cam and an auxiliary cam for withdrawing the said pistons.

4. A mechanism of the class described comprising an outer casing, a driving shaft, gearing interposed between said shaft and said casing for turning the latter, an inner rotor carrying part of said gearing and having a series of cylinders formed therein, the cylinders having ports communicating with the interior of said casing, a cam carried by said casing, the casing and cylinders being filled with a fluid, rocker arms pivoted upon the said cylinders and having rollers engaging the said cam, pitmen connecting the rocker arms with the said pistons whereby they will be moved in accordance with the surface of the cam and means for closing or partially closing the ports of the cylinders for retarding the movement between the cam and the inner rotor or completely locking the two together in accordance with the motion which it is desired to impart to the driven member.

5. A variable-speed power-transmission device having a driven member and a driving member, a casing, a hydraulic agent in said casing, gearing capable of imparting movement from the driving member to said casing, a series of cylinders forming an inner rotor and having ports communicating with the interior of said casing, a valve for controlling said ports, rocker arms carried by the rotor having anti-friction rollers therein, pistons in the cylinders and connected with said rocker arms, a cam in the said casing adapted to actuate the said

rocker arms for causing the pistons to move the hydraulic agent through said ports, and means for operating the said valve to check or cut off said hydraulic agent to control the relative movement of the said casing and the rotor, a sleeve adapted to rotate the said valve, a lever for operating said sleeve, and means upon said sleeve adapted to engage the said casing when the rotor and casing are moved at the same speed, whereby a positive communication between the parts will be had.

6. A mechanism of the class described comprising a driving shaft, a casing movable thereon, a gear actuated by said shaft, a rotor movable within said casing, and having gear holding means projecting therefrom, reducing gears mounted on said holding means, some of said gears meshing with the shaft driven gear, a gear carried by said casing, and engaging the other gears, a cam held by said casing, the rotor being provided with cylinders set tangentially, pistons in said cylinders, levers interposed between said pistons and the cam for moving the pistons inwardly, means for withdrawing the pistons, said means embracing an auxiliary cam, and a brake band adapted to engage the said casing for retarding its movement and reversing the action of the gears, the structure being such that the

rotor and the shaft driven thereby may be reversed in direction or stopped in action.

7. A driving means, a driven means, a plurality of cylinders, tangentially arranged on one of said members, pistons in said cylinders, means for controlling the movement of said pistons, rocker arms connected with said pistons and provided with cam engaging elements, a cam against which said elements bear, and a reducing gearing between said cam and driving member.

8. A driving member, a driven member, a plurality of cylinders carried by one of said members, pistons in said cylinders, a fluid in said cylinders, a rocker arm for each of said cylinders connected at one end with its piston and at its other end connected with one of said members, a cam engaging member intermediate the ends of said rocker arm for moving the same, a cam against which the same bears, a reducing gearing between said cam and driving member, and movable fluid confining means for each of said cylinders, substantially as described.

Signed at Los Angeles, county of Los Angeles, and State of California, this 2nd day of September, 1919.

ARNOLD HENRY JESSEN.
